LÉON GAUMONT, OF PARIS, FRANCE, ASSIGNOR TO SOCIETE DES ÉTABLISSEMENTS
GAUMONT, OF PARIS, FRANCE.

LOUD-SPEAKING ELECTROMAGNETIC RECEIVER.

Application filed January 23, 1924. Serial No. 688,080.

The said loud-speaking receiver, which can be mounted in a telephone circuit, comprises a large-surface diaphragm constituted by a sheet of pasteboard, paper or the like which is folded so as to form a great number of warped elements, the same being connected to an electro-magnetic receiver such as an electromagnet having an armature, whereby the sound waves will be greatly simplified, the whole device being mounted upon a support whose base is of sufficient size to offer all the required stability.

The appended drawings represent the said loud-speaking apparatus, Fig. 1 being a side elevation and Fig. 2 a perspective view of the rear part.

Referring to the drawings, the device comprises a support having a heavy base portion *c'* to which is integrally secured an upwardly curving arm *c*. Secured in any suitable manner to the underside of the upper extremity of arm *c* is a spider which consists of a central annular portion from which extend three radial arms *b* that are preferably spaced apart at an angular distance of 120°. Secured in any desired manner to the outer ends of the arms *b*, is an annular member or ring *a'* which engages and securely holds the periphery of a pleated diaphragm *a* of the Lumière type.

Mounted in the annular portion of the spider is an electromagnetic receiver *d* of the telephone type which is operatively connected in any desired manner to the center of the diaphragm *a*.

Suitable means are provided for connecting the electromagnetic device to the output side of an electric circuit. In the form shown, this means comprises terminal members *e* provided on the upper surface of the receiver, to which terminals are connected lead wires *f* which pass through a suitable passageway in the arm *c*. The upper end of this passageway terminates in the rear of the point where the spider is connected to said arm and directly over the terminals *e*. The central portion of the

passageway is formed as an open groove in the rear of the upper half of the arm *c* which groove communicates at its lower end with a passageway that terminates adjacent the lower end of the rear face of said arm. Preferably an adjusting member *g* is operatively connected to the element connecting the diaphragm and receiver for regulating the amplitude of vibration of said diaphragm.

What I claim is:

1. A device of the class described comprising in combination with a pleated diaphragm and an electromagnetic receiver connected thereto, a base, an upwardly curving arm integrally secured to said base, a spider having a central annular portion and a plurality of radial arms secured to the upper end of the supporting arm, and a vertically disposed annular member secured to the extremities of said radial arms. 60

2. A device of the class described comprising a support having a base portion and an upwardly curving arm portion, a spider comprising a central annular portion and a plurality of radial arms secured to the upper end of the supporting arm, an annular member secured to the extremities of said radial arms, a pleated diaphragm attached at its periphery to said member, electromagnetic means supported by the annular portion of said spider, and means operatively connecting said electromagnetic means and diaphragm. 70

3. A support for a loud speaker of the pleated diaphragm type comprising a base, an upwardly curving arm formed integrally with said base and having a passageway therein for receiving circuit connecting wires, a spider having a central annular portion for receiving an electromagnetic member and having a plurality of radial arms formed integrally therewith, and a ring secured to the extremities of said arms for supporting the diaphragm. 85

In testimony whereof I have signed this specification.

LÉON GAUMONT.
